UNITED STATES PATENT OFFICE.

CHRISTOPHER W. LEVALLEY, OF MILWAUKEE, WISCONSIN, ASSIGNOR TO CHAIN BELT COMPANY, OF MILWAUKEE, WISCONSIN, A CORPORATION OF WISCONSIN.

APPARATUS FOR DELIVERING AND DISTRIBUTING MATERIAL.

1,310,243.

Specification of Letters Patent. Patented July 15, 1919.

Application filed June 1, 1916. Serial No. 101,086.

To all whom it may concern:

Be it known that I, CHRISTOPHER W. LEVALLEY, a citizen of the United States, residing at Milwaukee, in the county of Milwaukee and State of Wisconsin, have invented certain new and useful Improvements in Apparatus for Delivering and Distributing Material, of which the following is a specification.

10 My invention relates to mechanism for distributing material that will flow, and it has been devised with especial reference to being used to deliver mixed concrete in street paving operations; although it is 15 capable of a wide variety of applications and uses. These distributing means include a spout that receives the mixed concrete from a receptacle in which it is contained, such as mixing machine, means for supporting, directing, and manipulating the spout so that the material shall be delivered at the desired places, and means for directing the material from the receptacle in which it is contained to the spout.

25 In the accompanying drawings—

Figure 1 is a side elevation of apparatus embodying my invention.

Fig. 2 is a top plan view of the same.

Fig. 3 is a front end view; and

30 Fig. 4 is a detail view in side elevation illustrating the parts in a different position from that represented in Fig. 1.

In the drawings, 16 indicates a receptacle adapted to contain the material to be distributed, the specific form of receptacle illustrated being a concrete mixing machine of the rotary type. This is mounted in suitable framework 17 from which projects a lower bracket 18 and an upper bracket 19.

40 In these brackets are supported, by vertical pivots 21, a swinging frame 22 constructed to form a pair of channels 1, 1, that incline upwardly and forwardly, or away from the receptacle 16, a cross-piece 23 uniting the lower ends of the channel frame pieces 1 with the lower vertical pivot 21, and a bracket 24 uniting the upper ends of the channel frame pieces 1 with the upper pivot.

45 25 indicates a spout to receive the material from the receptacle 16 and deliver it to the place or places where it is to be used. The inner end of the spout, that is, the receiving end thereof, is supported in the frame 22 and is vertically movable therein. 5 represents wheels secured to the spout and ar-

ranged to travel in the channels formed by the side frame pieces which thus operate to support and guide the spout in its up and down movements. The outer delivery portion of the spout is supported by a cable, 60 bar, or equivalent tension device, 2, extending from where it is secured, at 4, in the upper portion of the frame 22 to a pivoted yoke 3 secured to the spout.

6 represents a cable suitably connected, at 65 7, with the inner portion of the spout, whence it extends over a sheave 8 supported in the bracket 24 of the swinging frame, past guiding pulleys 26 supported by the bracket 19, and over a turning and guiding 70 pulley 27 on the framework 17, whence it continues to a drum 9 upon which it is wound. Alongside of the drum 9 and rigidly connected therewith is a larger drum 10 upon which is wound a cable 11 that extends to a winding drum 12, loosely supported upon a power shaft 13 mounted in the framework of the machine. A manually controlled clutch 14 serves as the means for connecting at will the winding drum 80 with the power shaft 13.

It will be seen that whenever the drum 12 is connected with the power shaft the cable 11 is wound thereon and drawn off from the drum 10, which is thereby rotated. The rotation of this drum turns with it the drum 9; and causes the cable 6 to be wound on its drum. This lifts the inner end of the spout, giving it an inclination, as indicated in dotted lines in Fig. 1, which may be sufficient 90 to cause the material that has been delivered to it to flow and be discharged at the desired place of use. As the inner end of the spout is thus elevated the spout as a whole turns about the connection of the suspending 95 tension member 2 with the spout as a pivot, so that its delivery end approaches the surface of the ground whenever material is to be delivered, thus tending to insure a gentle deposit of the material, which in the case of 100 freshly mixed concrete is very desirable.

The upward and forward inclination of the guideways in which travel the wheels 5 carried by the spout, causes the spout to be carried bodily forward and away from the receptacle 16, whenever its inner end is elevated so that it clears the end of the delivery chute 15 through which material is directed from the receptacle 16 to the spout 25, and under which chute the inner end of the spout 110

lies when lowered to receiving position. The spout 25 may be formed of separate sections arranged to be brought into alignment with each other and held to form a continuous conveyer, or to have the sections toward the delivery end adjusted to cause a delivery of material at different distances from the receptacle 16. Thus the spout may have an outer pivoted section 28 that is adapted to be 5 swung upwardly, as indicated in dotted lines in Fig. 1, to shorten the effective working length of the spout; and also an intermediate pivoted section 29 which may let down, as also indicated in dotted lines in Fig. 1, 10 and cause delivery at an intermediate point. These features of spout construction, however, are well known in the art and I lay no claim to having invented them.

It is important that the delivery of material from the receptacle 16 to the receiving end of the spout be controlled, so that whenever the spout is lifted to deliver its charge the supply from the receptacle 16 may be cut off. I therefore preferably interpose between the said receptacle and the inner end of the spout the following delivery-control devices.

30 indicates a shaft suitably supported in the framework 17 and on which is mounted 30 a wheel 31 by which the delivery control chute is operated. Keyed to the shaft 30 is a short arm 32 to which is pivotally connected a bent link 33. The link unites the arm 32 with a longer arm 34 extending from 35 a shaft 35 that extends across the machine and carries a pair of arms 36 that are secured fast to the swinging delivery chute 45. The parts connecting the shafts 30 and 35, to wit, the arm 32, the link 33, and the arm 40 34, are so disposed and shaped that when the delivery chute is in the position indicated in full lines in Fig. 1, delivering to the spout 25, the pivots of the link 33, uniting it respectively with the arms 32 and 34, 45 are in line with each other and with the axis of the shaft 30; that is to say, the parts are locked in a dead center relationship, so that pressure upon either end of the chute will not tend to disturb the said 50 relationship or cause the chute to be shifted from its delivery position. And again, when the parts are adjusted to the position indicated in Fig. 4, with the chute occupying a non-delivering or cut-off position, the pivots of the link 33 are again in line with the axis 55 of the shaft 30 and hence locked in dead center position, so that the chute is again held securely in this position. The arm 32 and link 33 are provided with contacting parts 37 that make the joint uniting these stiff in one direction, so that a rotation of the operating wheel 31 to turn the chute 45 from delivery to cut-off position causes a

positive movement of the link and the several connected parts of these delivery control devices. The change of position of the chute from delivery to cut-off position not only stops the delivery of material from the receptacle 16, but also takes the outer or projecting end of the chute somewhat out 65 of the path of the distributing spout 25. It also insures that any drip from the chute shall be carried back into the receptacle when it is turned into cut-off, non-delivering, position. While the form of delivery 70 control devices described and illustrated is that which I prefer, my invention is not limited in its useful applications to the specific devices shown.

By arranging the guide that controls the 80 movements of the inner end of the distributing spout as illustrated such end of the chute is carried bodily away from the receptacle 16 and from any delivery chute that may be associated therewith; and this bodily movement of the distributing spout 85 might be depended upon alone to clear the delivery chute when the distributing spout is lifted to cause the material to flow and be discharged.

The connection between the supporting tension member 2 and the distributing spout constitutes a shifting fulcrum about which the spout turns when adjusted upward and downward, such fulcrum both rising and advancing outward or away from the receptacle 16 when the inner end of the spout is elevated, but not to the same extent as the latter.

What I claim is:—

1. The combination with a receptacle for material and a chute delivering therefrom, of a spout for delivering the material, the inner end of which is located below the chute to receive material delivered from the 105 said receptacle, and guides for the inner end of the spout arranged to cause it to move bodily away from the said receptacle and from beneath the chute as the said inner end is elevated, and means for elevating the inner end of the spout.

2. The combination with a receptacle for material, of a distributing spout the inner end of which is located so as to receive material delivered from said receptacle, a frame in which the inner end of the spout is supported having guideways for directing its movements, the said guideways extending upwardly and away from the receptacle, means for lifting the inner end of the spout to cause it to assume an inclined position so as to discharge by gravity, and a tension member extending from the upper part of the said frame to the outer portion of the spout for suspending the latter.

CHRISTOPHER W. LEVALLEY.
